[57] CLAIM

The ornamental design for a rotatable holder for
cassettes and disks, as shown and described.

DESCRIPTION

FIG. 1 is a perspective view of a rotatable holder for
cassettes and disks showing my new design;

FIG. 2 is a top plan view thereof;

FIG. 3 is a bottom plan view thereof;

FIG. 4 is a front elevational view, the rear being identi-
cal thereto; and,

FIG. 5 is a right side elevational view, the left side being
identical thereto.

The top and bottom plan views are drawn at a reduced
scale to FIG. 1.
